TABLECLOTH

William Wolf, Philadelphia, Pa., assignor to Quaker Lace
Company, Philadelphia, Pa.

Application July 6, 1955, Serial No. 36,841

Term of patent 14 years

(Cl. D92—26)

The figure is a plan view of slightly more than a quarter section of the tablecloth showing my new design, the other three sections being identical with the section here disclosed, arranged in proper relation to complete the tablecloth. The section disclosed is shown over a dark background to bring out the details of the design.

I claim:

The ornamental design for a tablecloth, substantially as shown and described.
